Inventor

John F. Cordes:-
By his Atty., *W. H. Rowe,*

UNITED STATES PATENT OFFICE.

JOHN F. CORDES, OF CHICAGO, ILLINOIS.

TEMPORARY LOOSE-LEAF BINDER.

SPECIFICATION forming part of Letters Patent No. 710,763, dated October 7, 1902.

Application filed May 20, 1901. Serial No. 60,988. (No model.)

To all whom it may concern:

Be it known that I, JOHN F. CORDES, a citizen of the United States, residing at Chicago, in the county of Cook and State of Illinois, 5 have invented certain new and useful Improvements in Temporary Loose-Leaf Binders for Letters, Bills, or other Loose Sheets, of which the following is a full specification.

My invention relates particularly to that 10 class of temporary binders which employ a binding-strip having impaling-pins affixed thereto and a clamping-plate having holes therein to receive the said pins and a spring plate or plates for engaging the pins and 15 locking the clamping-strip at any desired point thereon. Heretofore a separate spring-plate detached from the clamping-strip has been employed and a spring-plate pivoted to the clamping-plate having notches in the 20 opposite sides of its ends and adapted to be swung off its pivot transversely to the impaling-pins to engage at its end notches therewith; but these spring-plates are not attached to the clamping-plate in such manner that the 25 latter may be freely lifted and removed from the pins and also adapted to take hold of the pins at each downward movement thereon without holding the spring-plate with the fingers.

30 The object of my invention is to provide a very simple spring locking-plate for the clamping-plate of a temporary binder which will be permanently attached thereto and will admit of the free movement of the clamping- 35 plate in either direction upon the pins and locked at any required position thereon.

My invention consists in certain features hereinafter particularly described and claimed, with reference to the accompanying 40 drawings, wherein—

Figure 1 is a perspective view of a temporary binder with my improved spring locking-plates attached to the clamping-plate thereof; Fig. 2, an enlarged rear elevation with the 45 clamping-plate and spring locking-plates in section, one of said spring locking-plates being held up to unlock the impaling-pin and the other spring locking-plate being held down by its spring tension to engage with and lock 50 the impaling-pin; and Fig. 3, a perspective view, upon a still larger scale, of one of the

spring locking-plates and its connections adapted to be affixed to the clamping-plate.

The binding-strip A carries the posts or impaling-pins B, and, as shown in Fig. 1, is 55 hinged to a bottom cover. The clamping-plate C has holes C' C² to exactly correspond in distance from each other with the distance of the pins from each other, thus to allow the clamping-plates to be freely moved thereon. 60

Spring locking-plates D are secured to the ends of the clamping-plate, their free ends having a hole d of larger diameter than the pins, thus to allow the ends of the plates D to vibrate from the locked position shown at the 65 left side of Fig. 2 to the unlocked position shown at the right side thereof. The apertures in the locking-plate are somewhat larger than and eccentric with those in the clamping-plate or the pin and so positioned as to 70 closely bind the pins when the locking-plates are in their locking positions. In their elevated or unlocked positions, however, the apertures are concentric with the pins, and being of a larger diameter allow the clamping- 75 plate to be freely moved or released from the pins.

The preferred mode of operating the spring locking-plates and of attaching them to the clamping-plates is shown in the drawings 80 more clearly in detail in Fig. 3, wherein two spring holder-plates E E' have oppositely-disposed screw-holes e at their ends through which screws F F' pass and screw into threaded holes in the clamping-plate C, one of said 85 screws F' also passing through a hole in the outer end of the spring locking-plate D. The plate E has a rectangular hole e' at the middle thereof and oppositely-disposed transverse grooves e² at the sides thereof to receive, 90 respectively, the tongue g and the journals g' of a lever G, and thus hold said lever and tongue in position to swing, respectively, beneath and alongside of the spring locking-plate, so that said plate may be held up at 95 its free end, as shown at the right of Fig. 2, to allow the clamping-plate to be moved freely on the pins or allow the same to be pressed down and clamp the said pin, as shown at the left of Fig. 2, to securely hold 100 the clamping-plate thereon when the letters are to be clamped upon the binder.

All of the parts comprising the locking device may be stamped out and easily fitted together and permanently secured to the clamping-plate truly in position and the cost of the 5 binder and locking device reduced to the minimum.

For large binders the device above described has proved light, strong, inexpensive, and most effective under all conditions.

10 I claim as my invention and desire to secure by Letters Patent—

1. In a temporary binder the combination with a binding-strip of impaling-pins rigidly secured thereon, a clamping-plate apertured 15 to receive the impaling-pins, oppositely-disposed spring holder-plates secured on the clamping-plate, a spring locking-plate secured at one end on each holder-plate and apertured to receive one of the impaling-pins and act- 20 ing normally to positively engage the same, said apertures in the locking-plate when said plates are in their locking position being eccentric with said pin thereby clamping the pin in the apertures thereof and in the clamp- 25 ing-plate, a pivotally-supported lever hav-

ing a bearing on the holder-plate and adapted to engage and to lift the locking-plate and a lever-arm extending outwardly and laterally of the locking-plate and adapted for manual engagement.

2. A lock for temporary binders comprising in combination a spring holder-plate apertured to receive an impaling-post and also apertured to permit of attachment with a clamping-plate, a lever pivotally engaged on 35 the holder-plate by means of a transverse shaft, a spring-plate secured at one end on the holder-plate and normally lying flat along the top thereof and having an aperture there- 40 in to receive the impaling-post out of register with the like aperture in the holder-plate, and a tongue operated by the lever and acting to lift the end of said spring locking-plate to bring the aperture therein into register with that in the holding-plate.

JOHN F. CORDES.
